UNITED STATES PATENT OFFICE.

JOHN ERICKSON, OF CHICAGO, ILLINOIS, ASSIGNOR, BY MESNE ASSIGNMENTS, TO FIRST TRUST AND SAVINGS BANK, TRUSTEE, OF CHICAGO, ILLINOIS.

TELEPHONE PARTY-LINE SYSTEM.

1,181,093.

Specification of Letters Patent. Patented Apr. 25, 1916.

Application filed September 15, 1906. Serial No. 334,768.

To all whom it may concern:

Be it known that I, JOHN ERICKSON, a citizen of the United States of America, and resident of Chicago, Cook county, Illinois, have invented a certain new and useful Improvement in Telephone Party-Line Systems, of which the following is a specification.

My invention relates to automatic telephone exchange systems of that particular type in which the subscribers use ground connections at the substations for transmitting electrical impulses over the telephone lines to operate the selectors and connectors or other suitable automatic switches at the exchange or central station; and it relates more particularly to a telephone exchange system of this character in which a plurality of substations are located on one telephone line, and in which each party line substation is provided with a lock-out relay for preventing interference by a third subscriber when two subscribers are already in possession of the line.

The principal object of my invention is to provide means for preventing a flow of current through the condensers on a party line when a subscriber takes down his receiver; and for thus preventing the calling subscriber's lock-out relay from becoming energized by the sudden connection of all the substation condensers in multiple with the grounded pole of the battery; for in cases where several substations are located on a line, necessitating the use of a corresponding number of condensers bridged in parallel across the line, I find that the total capacity is so great that a static charging is liable to occur, sufficient to energize the lock-out relay of the calling subscriber, even though the telephone line is free and in normal condition; and it is for this reason that the principal object of my invention is, as I say, to provide means for enabling the subscriber on a party line, when the latter is not in use, to take down his receiver without causing such a static charging of the condensers on the line as will be liable to energize his lock-out relay, as will hereinafter more fully appear.

It is also an object, of course, to provide certain details and features of improvement and combinations which may be found use-

ful in various connections and for various purposes in telephone systems in general.

To the foregoing and other useful ends, my invention consists in matters hereinafter set forth and claimed.

In the accompanying drawings, Figure 1 is a diagram of a section of a telephone system embodying the principles of my invention. In said figure a number of party line telephones A, B, C and D are indicated across the line that terminates in a step-by-step automatic switch E at the central office. Fig. 2 is also a diagram showing more in detail the application of my invention to an automatic party line telephone system, only two substations A and B being shown.

The telephones A and B shown in Fig. 2 may be of any suitable or approved type. The automatic switch E may also be of any suitable type, such as the selector described in United States Letters Patent No. 815,321, granted March 13, 1906, to Keith, Erickson and Erickson. In the said patent the subscriber's vertical and rotary line conductors 2 and 3 terminate directly in the respective vertical and rotary line relays 4 and 5. As herein shown, the connections are modified to the extent that the rotary line conductor 3 terminates in a switch shaft spring 6 controlled by the switch shaft 7, which spring, when the switch shaft is raised, engages the spring 8, at which time the rotary line conductor 3 is extended to the rotary line relay 5, as usual; but when the switch shaft is in normal position the said spring 6 is maintained in engagement with the spring 9 and, therefore, with the high resistance coil 10 which is grounded at G.

The substation is provided with the usual receiver 11, transmitter 12 and switch-hook 13, and also with the ringer 14 that is normally bridged across the line conductors 2 and 3 through the condenser 15. When the switch-hook 13 rises, however, the ringer circuit that passes through the ringer springs 16 and 17 is broken, since the said springs are adapted to separate when the weight of the switch-hook is removed from the spring 16. The telephone is provided with a dial (which is not shown) provided with numbers on its circumference, and with suitable finger-holes for guiding the subscriber in sending electric impulses for op-

erating the switches at the central office. To accomplish this the dial must be rotated first clockwise and then allowed to return to normal position by a counter-clockwise rotation. The dial is fastened onto the shaft 18 to which there is also attached a dog 19. The substation is provided with a lock-out relay 20 that is constructed with an elongated armature 21. This armature 10 is provided with a hooked terminal that is adapted to engage an eye in the dog 19, and the arrangement is such that when the relay 20 energizes the armature 21 is attracted and the dog 19 is locked by said armature so 15 that the subscriber is unable to turn his dial. It is intended that this locking operation shall only occur after the first subscriber that seizes the line operates the selector switch E so as to close the normally open 20 circuit between the switch shaft springs 6 and 8. Since the energizing circuit for the relay 20 comprises the said springs 6 and 8 it will be evident that said relay should not energize until the said springs are in 25 contact. It happens, when there are a great number of substations bridged across the line, as indicated in Fig. 1, that the condensers 15 (which are connected in multiple) aggregate a capacity which permits a 30 current flow from the substation ground G' at substation A through the coil 20, springs 22 and 23 to the rotary line conductor 3, thence to the conductor 24 at substation B, through the ringer springs 25 and 26, through the 35 ringer 27, condenser 15 to the vertical line conductor 2, thence through the vertical line relay 4 at the switch E to the battery B' and to the ground. A similar discharge would occur through the station C, station D, and 40 so on. When there are only a couple of substations across the line this trouble from a discharge may not become apparent, but as the number of substations increases it becomes more and more apparent. It is found 45 that by normally retaining the high resistance coil 10 at the selector E in connection with the rotary line conductor 3 the condensers 15 are prematurely charged, so that connecting the substation relay 20 with the 50 rotary line conductor 3, when the springs 22 and 23 close in contact, does not operate the relay 20. It will thus be very evident that my invention thus considered is applicable to any kind of a line where a relay 55 may be energized by the discharge through a condenser, or condensers in multiple, or otherwise. Thus, as stated, the condensers on the party line are normally charged, and the sudden closure of connection between 60 ground and a substation on the line does not, therefore, tend to energize the lock-out relay of the calling subscriber—that is to say, in cases where the line is clear or in normal condition, and the calling subscriber entitled to the use of the line. Furthermore,

it will be seen that I provide a telephone line which is normally grounded at the exchange or central station, and which is thus normally connected with the grounded pole of the battery or centralized source of current. Preferably, it is the so-called rotary 70 side of the telephone line which is normally grounded at the central station. Thus, all of the condensers on the party line are normally connected over one side of the telephone line with the grounded pole of the source of operating current at the central station. With this arrangement, as explained, the condensers are normally charged from the positive pole of the battery, and the adding of another ground at 75 the calling substation, when the subscriber removes his receiver, does not produce a current flow through the condensers. 80

While my invention, as previously stated, 85 relates more particularly to automatic party line telephone systems, it will be understood, of course, that I do not limit myself to systems of this particular character, as my invention is also applicable to other 90 systems, either automatic or otherwise, such, for example, as ordinary manual systems in which provision is made for locking the calling subscriber out when the line is already in use, or in which electro-magnets for 95 some suitable purpose are employed at the substations.

What I claim as my invention is:—

1. In a telephone exchange system, the combination of a telephone line, a plurality of substation condensers bridged in parallel across said line, a normally open substation ground associated with each condenser, an electro-magnet associated with each condenser, means for closing circuit 100 from ground through the coil of the electro-magnet to the condensers in parallel when the calling subscriber takes down the receiver associated with such magnet, a centralized source of current having one pole 105 grounded, and a normally closed ground connection for one side of the telephone line, said line being normally disconnected at one side from the non-grounded pole of the source of current, and normally connected 110 with the non-grounded pole of said source of current at the other side thereof.

2. In a telephone exchange system, the combination of a telephone line, calling mechanism therefor, a common battery having one pole grounded and the other pole normally connected with the line, a normally closed connection between the ground and one side of the line at the central station, and means for opening the ground 120 connection and closing the line circuit when the subscriber first operates said calling mechanism.

3. In a telephone exchange system, the combination of a telephone line, a common 125

5 battery having one pole grounded and the other pole normally connected with the line, an automatic trunk-selecting switch having a normally closed connection between one side of the line and the grounded pole of the battery at the central station, a resistance in said connection, and means for disconnecting said resistance during talking.

4. In a telephone exchange system, the 10 combination of a telephone line, a plurality of substations on said line, a condenser at each substation, said condensers being in multiple, a battery at the central station, an automatic selecting switch for extending 15 a connection from said line, and means for keeping said condensers charged with battery current while the line is in normal condition, each condenser normally connected with and between both poles of the battery, 20 and said battery normally bridged across the subscriber's telephone line, for the purpose set forth.

5. In a telephone exchange system, the combination of a telephone line, a plurality 25 of substations on said line, a condenser at each substation, an electro-magnet at each substation, a central source of current, a hook-switch for each substation, means for closing circuit through all the condensers in 30 parallel, and through one magnet, when a subscriber takes down his receiver, and means for preventing energizing of the one magnet by current flow through the condensers in parallel.

35 6. In a telephone system, a battery, a line having its two sides normally connected with opposite sides of said battery, a plurality of condensers normally bridged across the said line, an impulse transmitter, and means by which a calling subscriber, by the first impulse transmitted, disconnects one side of the line from one pole to the battery and connects the same with the other pole thereof.

45 7. In a telephone system, a telephone line, a plurality of condensers normally bridged across the same, a battery having one pole grounded and the other pole connected with one side of the line, the other side of the 50 line being grounded, an impulse transmitter, and means by which a calling subscriber, by the first impulse transmitted, cuts off the ground from the line and connects that side of the line with the non-grounded 55 pole of the battery.

8. In a telephone system, a battery, a plurality of condensers connected in parallel in a normally closed line circuit containing said battery, an impulse transmitter, and means 60 at the central station by which a calling subscriber at any condenser disconnects one pole of the battery and connects the disconnected side of the circuit with the other pole thereof on the first impulse transmitted.

9. In a telephone exchange system, the

combination of a telephone line, a plurality of substation condensers bridged in parallel across said line, a normally open substation ground associated with each condenser, an electromagnet associated with each condenser, means for closing circuit from ground through the coil of the electromagnet to the condensers in parallel when the calling subscriber takes down the receiver associated with such magnet, a centralized 70 source of current having one pole grounded, a normally closed ground connection for one side of the telephone line, and means having one motion to select groups and another motion to connect with a line in any selected group, responsive to grounding of the line at any calling substation.

10. In a telephone exchange system, the combination of a telephone line, a common battery having one pole grounded and the 85 other pole normally connected with one side of said telephone line, relay windings included in the connection between the line and the non-grounded pole of the battery, a normally closed connection between one 90 side of the line and the grounded pole of the battery, the line being normally open between the said ground connection and the battery connection, subscriber-controlled means for opening said ground connection, 95 and means having one motion to select groups and another motion to connect with a line in any selected group, responsive to grounding of the line at any calling substation.

100 11. In a telephone exchange system, the combination of a telephone line, a plurality of substations on said line, an electromagnet at each substation, a condenser at each substation, a battery at the central station, 105 means for keeping said condensers charged with battery current while the line is in normal condition, there being a circuit from each magnet through the condensers in multiple and to the battery, and means having 110 one motion to select groups and another motion to connect with a line in any selected group, responsive to grounding of the said telephone line.

115 12. In a telephone exchange system, the combination of a telephone line, a plurality of condensers and substations allotted thereto, means for locking out a calling substation if the line is in use, and means whereby any calling substation is not locked out 120 when the line is idle; the first said means comprising a battery, a subscriber's line, a substation magnet, and a normally open circuit for energizing said magnet, including the said battery and subscriber's line; the second said means comprising a battery, the subscriber's line, condensers connected with one terminal of said battery, and a resistance-coil allotted to the line and connected 125 to the other terminal of the battery, the said 130

battery adapted to charge the said condensers over a circuit including the subscriber's line and the said resistance-coil; and means having one motion to select groups and another motion to connect with a line in any selected group, responsive to grounding of the line at any calling substation.

13. In a telephone exchange system, the combination of a telephone line, a plurality of substations on said line, a condenser at each substation, an electromagnet at each substation, a central source of current, a hook-switch for each substation, means for closing circuit through all the condensers in parallel, and through one magnet, when

a subscriber takes down his receiver, means for preventing energizing of the one magnet by current-flow through the condensers in parallel, and means having one motion to select groups and another motion to connect with a line in any selected group, responsive to grounding of the line at any calling substation.

Signed by me at Chicago, Cook county, Illinois, this 12th day of September, 1906. 25

JOHN ERICKSON.
